TRAFFIC LIGHT

Albert E. H. Modern, West New York, and
James L. Burke, Weehawken, N. J.

Application July 14, 1942, Serial No. 450,872

6 Claims. (Cl. 177—327)

The present invention is concerned with traffic signal units of the type used on streets and automobile highways.

Where pairs of red and green lenses are employed for the respective stop and go signals and particularly where four pairs of these are used in each unit, the unit is not only expensive, bulky and heavy, but its operation entails difficulty. Among these are the confusing character of the signal where strong sunlight or a head light shines upon and is reflected from the colored lenses, both of which, under such conditions, would appear to be illuminated with almost equal brightness. Moreover, the driver is obliged to shift his line of vision in order to detect a change in color which constitutes a source of annoyance that is aggravated where illuminated colored commercial and advertising signs, particularly animated signs, abound.

It is among the objects of the present invention to provide a traffic signal unit which obviates all of said objections and which more particularly eliminates the use of colored lenses, which exhibits the stop and the go signal in identically the same location, and the clarity and unambiguity of which signals will not be impaired even when strong sunlight or illumination from a strong automobile head light is projected thereon.

Another object is to provide a signal unit of the above type which is relatively inexpensive and of small bulk and which operates reliably with the use of but two lamp bulbs and is so light in weight that it may be suspended directly in the center of the street intersection to control traffic in both directions on each of the streets with a minimum of interference from other sources of illumination, thus to obviate the need for traffic signal units on two or all four of the street corners.

In the accompanying drawing in which is shown one of various possible embodiments of the several features of the invention,

Fig. 1 is a perspective view of the unit.

Fig. 2 is a transverse sectional view taken on line 2—2 of Fig. 1.

Fig. 3 is a transverse sectional view taken on line 3—3 of Fig. 2, and

Fig. 4 is a perspective view of the interior construction of the unit, the lamps and filter plates being removed, more clearly to reveal the structure.

Referring now to the drawing, the traffic light unit comprises a square box 10 which may be of suitable cast or sheet metal construction, one of the sides or faces of which is shown at 11. The unit has a bottom plate 12 and, if desired, a

pyramidal roof 13. Face plate 11 of the box has a central window opening which is equipped with a bezel 14 embracing the rim of a colorless lens 15.

In the embodiment shown, for controlling two-way traffic at street intersections, such lenses are provided in each of the four sides of the box. A cruciform septum 16 extends horizontally in the diametral plane of the respective window openings and lenses. That septum has a generally square hub 17 and four arms 18 radiating outward therefrom, the sides of each arm desirably diverging and its ends being secured, desirably by soldering, brazing or welding into the corners 19 of the box as shown. Consecutive diametral arms of the septum are spaced from each other as at 20 by a distance greater than the diameter of the lens so as to afford a free passage for light through the respective lenses from the light source within the box. That light source desirably comprises two lamp bulbs 21 and 22 in corresponding sockets 23 and 24 mounted upon the respective faces of the septum hub 17. Upstanding walls 25 extend obliquely relative to the face plates, preferably substantially diagonally inward from the respective vertical edges of the box, at right angles to the septum 16 and symmetrically along the respective arms 18 of the septum. These upstanding walls extend both above and below the plane of the septum and said walls are desirably brazed, soldered or welded in place. Each of the upstanding walls 25 is triangular in shape as shown, the outer edges of the respective walls converging obliquely inward from the corners of the box to substantially the corners of the septum hub 17, as shown.

Light filter plates or sheets 26, each of the shape of an equilateral trapezoid, are desirably supported on the structure thus far described. Thus, referring to Figs. 2 and 3 for instance, the longer base 27 of the trapezoidal filter plate 26 extends along the upper edge of the box, the shorter base 28 thereof along the hub of the septum and the sides thereof are supported in metal channels 30 upon the converging outer edges of two consecutive upstanding walls 25. In like manner filter plates will be provided along each of the four sides of the box and a like set of filters will be similarly mounted in the lower half of the box below the septum. The lower filter plates are kept from dropping out of place by the bottom plate 12.

Thus, the interior structure comprises four square generally pyramidal conformations, the base of each comprising the corresponding face of

the box, the apex of each comprising a ridge determined by the corresponding side of the septum hub 17, two opposed side walls 25 of the pyramidal structure being opaque and the other opposed side walls being the filter plates.

It will be obvious that the opposite filters 26 and 26' will be of color contrasting with that of the intervening pair of opposed filters. Filters 26 and 26' might be red and the intervening pair green. Similarly, the corresponding opposed filters 26^a and 26^b below the septum 16 would be green while the intervening pair of filters would be red. In other words, the filters at opposite sides of the septum would be displaced by a right angle with respect to each other.

In operation, upon the illumination of lamp 21 the filters 26 and 26' would pass red light, so that the color at the window lenses 15 and 15' would be red, while the same lamp would cause the other pair of window lenses at right angles thereto to register green. Upon extinguishing lamp 21 and illuminating the lower lamp 22 the color situation would be reversed, the filters 26^a and 26^b causing the opposed lenses 15 and 15' to show green while the intervening filters would cause a red light to appear at the other pair of opposed lenses.

The light passing each filter has free access to the associated lens through the large opening 28 between the arms of the cruciform septum. The light will be of the color of the filter, undisturbed in any wise by the color of the contiguous filter, since no part of the latter is interposed in the path of rays from the lamp to the lens. The opaque upstanding walls 25 prevent any mixture of light laterally.

While the drawing shows the arrangement for two-way traffic at intersecting roads, it will, of course, be obvious that the invention could be used for controlling traffic along a single road only, if desired. In that relation the windows on one pair of opposed faces of the box would be closed and only two pairs of filter plates would be used. The lateral walls and the filters in that case might be rectangular rather than trapezoidal in construction, the upstanding walls that laterally support the filter plates extending along the closed side walls of the box unit, that box structure itself closing the space between the oblique edges of opposed filters.

It will likewise be understood that in its broadest aspect the invention could also be applied to control traffic in only one direction on a single road, in which event only one window and the associated pair of filter plates need be used.

It will thus be seen that the structure is light, simple and inexpensive, that it obviates the use of colored lenses, greatly reduces the number of light bulbs required, reduces the bulk of the equipment and affords the signal, regardless of color, always at the same place, for ease of vision and avoids confusion or ambiguity of signal by reflection of sunlight or light from a headlamp.

By reason of the lightness of the equipment it is practical, as suggested in Fig. 1, to mount the same on a cross-wire 33 from an eye 34, directly in the center of the street intersection. It will, however, be understood that the invention may be used on traffic stanchions, if desired, and applied in any conventional or desirable manner.

It will be understood that in the simplified embodiment serving only a single road and incorporating no more than two opposed lenses, the box could, if desired, be positioned at right angles

to the position shown, the septum 16 extending in a vertical rather than in a horizontal plane.

As many changes could be made in the above equipment and many apparently widely different embodiments of this invention could be made without departing from the scope of the claims, it is intended that all matter contained in the above description or shown in the accompanying drawing shall be interpreted as illustrative and not in a limiting sense.

Having thus described our invention, what we claim as new and desire to secure by Letters Patent of the United States:

1. A traffic light unit comprising a rectangular box having a face plate provided with a window opening, a horizontal septum within and midway between the top and bottom of said box, a pair of vertical walls extending obliquely inward from the lateral edge of said face plate and across said septum, the outer edges of said vertical walls extending obliquely from the respective corners of said face plate to the septum, plane filters of contrasting color supported at their outer edges near the respective upper and lower edges of the face plate, laterally upon the outer edges of the upstanding walls and engaging the horizontal septum at their inner edges and lamps attached to opposite faces of said septum in back of the respective filters.

2. A traffic light unit comprising a box having a face plate equipped with a window, a rectangular generally pyramidal structure of which the said plate constitutes the base and which extends rearward therefrom, said structure having a ridged apex and having one pair of opaque triangular side faces, the other pair of side faces comprising equilateral trapezoidal light filter plates of contrasting color, a lamp support extending at right angles to said face plate and rearward from said ridged apex and lamps at opposite faces of said support associated with the respective filter plates.

3. A rectangular traffic light unit comprising a casing having two pairs of opposed window openings, four pairs of symmetrically arranged light filters, each pair being of contrasting colors, said pairs extending obliquely behind the respective windows, means supporting said light filters in fixed relation, the filters behind the respective windows being spaced from each other at their inner ends near the midsection of the unit, a hub at said midsection supported by said light filter supporting means, and a pair of lights carried by said hub extending at opposite sides thereof and disposed in the spaces framed by the respective filters at the corresponding side of the hub, and means for projecting light selectively upon the filters at either side of said hub.

4. A traffic light unit comprising a rectangular box having opposed face plates each equipped with a window, a septum in a plane diametral of said windows, generally rectangular pyramidal structures converging inward from about the respective windows, each of said pyramidal structures having a pair of opposed opaque side walls extending generally diagonally of the box at right angles to said septum, the other pair of opposed side walls being of light filtering material of contrasting color and a pair of lamps projecting from opposite faces of the central part of said septum and between the corresponding pairs of light filters of opposed pyramidal structures, said septum affording an opening adjacent each window.

5. A traffic light unit comprising a rectangular

box having side walls and windows in a pair of opposed said walls, a septum in the diametral plane of said windows extending to and rigid with said walls, said septum having deep openings across the entire diameters of the respective window openings, light filters extending obliquely from the opposite edges of the respective opposed walls to the septum and contacted by said septum at their inner edges and in spaced relation, the opposed filters at opposite faces of the septum being of contrasting color, an opaque structure closing the space between the corresponding lateral edges of the opposed filters associated with the respective windows, and lamps supported on opposite faces of the septum between the respective pairs of filters.

6. A traffic light unit comprising a rectangular box having windows in the four sides thereof, a

cruciform septum having a hub and arms in the diametral plane of said windows, lamps supported by said hub and extending from opposite faces thereof, generally diagonal walls extending inward from the respective corners of said box symmetrically of the arms of said cruciform septum, said walls having oblique outer edges converging at the septum, and eight equilateral trapezoidal filter plates, the longer bases of which engage the respective upper and lower edges of the box, the sides of which are supported upon the oblique outer edges of the respective diagonal walls and the shorter bases of which engage the septum, each pair of horizontally opposed filters being of the same color, each pair of contiguous filters being of contrasting color.
